ANTENNA HOUSING OR SIMILAR ARTICLE

Ralph N. Leonard, Crystal Lake, Ill., assignor to The Radion Corporation, Crystal Lake, Ill., a corporation of Illinois

Application March 11, 1959, Serial No. 54,940

Term of patent 7 years

(Cl. D26—14)

Fig. 1 is a perspective view of an antenna housing showing my new design;

Fig. 2 is a rear elevational view;

Fig. 3 is a side elevational view;

Fig. 4 is a top plan view; and

Fig. 5 is a bottom plan view.

The slots for attachment and the dipole extensions are shown in dotted lines for purposes of illustration only.

I claim:

The ornamental design for an antenna housing or similar article, substantially as shown and described.
